CLAIM

The ornamental design for a stand for test tubes or the like, as shown.

DESCRIPTION

FIG. 1 is a perspective view of a stand for test tubes or the like, showing my design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a bottom plan view thereof.

The broken line disclosure of the test tubes is for illustrative purposes only and forms no part of the claimed design.

FIG. 1.

FIG. 2.

FIG. 3.

FIG. 4.

FIG. 5.

FIG. 6.

FIG. 7.
